CARRIAGE ESCAPEMENT DEVICE

Benjamin Grady, Washington, D. C.

Application December 14, 1943, Serial No. 514,292

5 Claims. (Cl. 164—111)

(Granted under the act of March 3, 1883, as
amended April 30, 1928, 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to a carriage escapement device, and more particularly to improved means for controlling the advance and escapement of a machine carriage, such as the card carriage of a tabulating card punching or verifying machine.

The present invention may be conveniently explained as applied to tabulating card punching machines. It will be obvious, however, from an understanding of this invention that it may be used to advantage in other types of machines having a shiftable carriage and requiring a device to control the escapement movement of the carriage across the machine.

A well known form of tabulating card has a series of evenly spaced columns to be provided with data by a punching machine. Conventional and well-known tabulating card punching machines usually have a carriage for advancing a card to position the individual card columns opposite the machine punching dies, the card carriage being advanced under the control of an escapement device. Heretofore, the escapement device has comprised an escapement rack and a skip bar. The escapement rack enabled the card carriage to be advanced step by step for positioning the card columns opposite the punching dies and in the order the columns appear on the card. The skip bar was carried by the escapement rack and so controlled the carriage operation that certain card fields or columns would skip the punching dies and therefore would not be punched. This skip bar heretofore has been provided in the form of a solid bar having notches in its lower edge for temporary mounting on headed pins projecting from the escapement rack. The upper edge of the skip bar heretofore has been machined to provide depressed portions opposite the escapement teeth of the escapement rack for the card fields (columns) to be punched and raised (integral) portions opposite the escapement teeth for the card fields to be skipped. Thus the card carriage would have normal single column escapement in the card fields corresponding to the depressions in the skip bar and would have a plural column escapement in the card fields corresponding to the raised portions in the skip bar.

The described conventional skip bar has proven to be relatively expensive, since it must be precisely formed and is designed for only one escapement pattern. For each new or different escapement pattern, a new skip bar is required and has to be manufactured and mounted on the escapement rack. As an illustration, let it be assumed that a tabulating card punching machine has

been operating with a skip bar which provides for card columns 1 through 5, 9 through 12, and 18 through 25, to be punched individually in a normal single column escapement and for card columns 6 through 8 and 13 through 17, to be skipped in two plural column escapements. If the punching machine is next to be operated with cards in which columns 6 through 8 and 13 through 17 are the only columns to be punched, a new skip bar must be manufactured and installed in the machine to replace the one previously used, which is frequently discarded or lost.

It is, therefore, an object of this invention to provide a carriage escapement device which has a readily adjustable escapement pattern.

Another object is to provide a carriage escapement device comprising an escapement rack and a skip bar which may be united to form a permanent assembly, and means which may be removably positioned on and locked to the skip bar to provide any desired escapement pattern.

Still another object is to provide a novel carriage escapement device having a skip bar, removable escapement pattern pins, and efficient means for locking the pins to the skip bar.

Other objects and advantages of this invention will be apparent from the following specification, the appended claims, and the accompanying drawing, wherein

Fig. 1 is a perspective view of a tabulating card punching machine embodying the present invention. Fig. 1 illustrates a carriage escapement device of the present invention and so much of a conventional punching machine as is necessary to an understanding of this invention.

Fig. 2 is a front elevational view on enlarged scale of the escapement rack, the skip bar, the escapement pattern pins, and pin locking means of Fig. 1, parts being broken away in Fig. 2 for purposes of illustration.

Figs. 3 and 4 are elevational views of two of the pins of Figs. 1 and 2.

Fig. 5 is a cross-sectional view taken on line 5—5 of Fig. 2.

Fig. 6 is a cross-sectional view taken on line 6—6 of Fig. 2. It will be noted that the views of Figs. 5 and 6 are identical except that the pin and the locking needle of Fig. 6 are omitted in Fig. 5.

Fig. 7 is an exploded view of the escapement rack, the skip bar, and the pin locking needle of Fig. 5.

Referring now to the drawings, Fig. 1 illustrates a tabulating card punching machine having a conventional base 10, which slidably supports a card carriage 11. The carriage 11 has a card pusher 12 and a card guide 13. A tabulating card (not illustrated) to be punched is placed on the base 10 and between the pusher 12 and the guide 13. The carriage 11 and the card (not shown)

then move together relative to the machine base or frame 10.

The carriage 11 also includes a conventional escapement rack 14 having its upper edge formed with the usual escapement teeth 16 (one tooth for each column of the tabulating card) and its lower edge formed with the usual gear teeth 17. A carriage handle 18 enables the machine operator to shift manually the carriage 11 toward the right hand end of the machine (Fig. 1) to prepare the machine for a tabulating card punching operation. The drive for the carriage 11 in the reverse direction (see arrow in Fig. 1) is provided by a conventional spring-controlled gear (not shown) which meshes with the gear teeth 17 of the escapement rack 14.

Other conventional machine parts illustrated in Fig. 1 include a locking pawl 18, an escapement pawl 19, and the skip lever 21. The locking pawl 18 engages a tooth 16 of the rack 14 and locks the carriage 11 against movement during each punching operation of the machine, at which time the escapement pawl 19 and the rack 14 are disengaged. The escapement pawl 19, when it engages a tooth 16 of the bar 14, permits a one-tooth movement of the bar 14 and a corresponding (one card column) movement of the carriage 11. Normally, the pawls 18 and 19 alternate in their engagement with the rack 14 to provide a single column escapement movement of the carriage 11 relative to the conventional bridge 20 which supports the usual key-controlled punches (not shown). The skip lever 21 is supported and operates in conventional manner to control the escapement pawl 19 for plural column escapement movements of the card carriage 11.

The skip lever 21 is controlled by escapement pattern pins 41 in a skip bar 31. This skip bar 31 at its inner side or face 36 and from one end to the opposite end is provided with a channel 32. The skip bar 31 is also provided with a plurality of sockets 33 for the pins 41. The spacing of the axes of the sockets 33 corresponds to the spacing of the centers of the teeth 16. Thus in the assembled relation of the skip bar 31 and the escapement rack 14, each pin socket 33 is opposite a tooth 16. The axes of the sockets 33, in a preferred embodiment of this invention and as illustrated in Figs. 5 and 6, are perpendicular to the upper face or edge 34 of the skip bar 31 and extend in a plane parallel to the skip bar face 36 in which the channel 32 is formed.

Each of the escapement pattern pins 41 has a head 42 and a shank 43. The shank 43 is adapted to fit snugly any one of the sockets 33. The extent that a shank 43 may be inserted into a socket 33 is limited by the pin head 42 (see Fig. 6) which has a diameter or size somewhat larger than the diameter of a socket 33. The pin shanks 43 are preferably of circular cross-section or cylindrical shape to conform to the cylindrical shape of the sockets 33. Each pin shank 43 intermediate the opposite ends thereof is provided with a notch or peripheral groove 44 (Fig. 6).

The channel 32 extends in parallel relation to the skip bar face or edge 34 and is spaced therefrom a distance corresponding to the spacing of the groove 44 and the head 42 of a pattern pin 41. The channel 32 also overlaps or intersects a side of each of the sockets 33, as illustrated in Fig. 5. This intersection results from the channel 32 having a depth (horizontal dimension in Fig. 5) which is greater than the spacing of the sockets 33 relative to the skip bar face 36, but which

is less than the spacing of the axes of the sockets 33 relative to the skip bar face 36.

The skip bar 31 is secured to the escapement rack 14, as by means of rivets 37 (Fig. 2), with the skip bar face 36 abutting a side face of the escapement bar 14, as illustrated in Figs. 5 and 6. In this assembled relation, the escapement rack 14 closes the open side of the skip bar channel 32, and the rack 14 and the bar 31 form a passage 10 which is open at one or both ends of the skip bar 31 to receive the locking needle 51 in a longitudinal, sliding movement. The needle-receiving passage (and also the channel 32) is conveniently formed with a square cross-section which conforms closely to the diameter of the locking needle 51. The locking needle 51 is preferably of circular cross-section, but may be of square or other suitable cross-sectional shape. The needle 51 should be of such cross-sectional shape that when inserted into the passage formed by the channel 32, the needle 51 engages the inner side face of the escapement bar 14 and extends laterally therefrom into each of the sockets 33 and into each of the grooves 44 of pins 41 positioned in the skip bar sockets 33. The needle 51 then will lock each pin 41, which is seated in a socket 33, to the skip bar 31 and the escapement rack 14.

One end 52 of the needle 51 is pointed to facilitate its placement in pin-locking position. The other needle end 53 is angularly bent to serve as a handle and to act as a stop for preventing such insertion of the needle that it may not be readily removed from the channel 42 when desired.

The escapement device of this invention is characterized by its adaptability to form as many escapement patterns as there are possible combinations of the pin sockets 33. When use of the machine requires a change in its escapement pattern, any or all of the pins 41 may be removed from the skip bar 31 after they are released by removal of the locking needle 51. A desired escapement pattern is then secured by inserting a number of the pins 41 in selected sockets 33. A pin 41 is inserted in each socket 33 which corresponds to a card column (not shown) that is not to be punched. Each socket 33 which corresponds to a card column (not shown) that is to be punched remains unoccupied.

The pin shanks 43 are all of the same form and construction. Some of the pin heads 42' (see Fig. 4) are tapered to serve as skip lever cams. The other pin heads 42 (Figs. 3 and 6) have flat tops and act as elevated rest for the skip lever 21. When a single card column is to be skipped and is located between two card columns to be punched, the socket 33 corresponding to the column to be skipped is provided with a pin 41 having a tapered head 42', as in Fig. 4. When a group of columns are to be skipped and form a continuous field, the socket 33 corresponding to the leading column in the advance of the card carriage 11 is provided with a pin 41 of the type illustrated in Fig. 4. The sockets 33 corresponding to the remainder of the columns in the field to be skipped are provided with pins 41 having flat top heads, as illustrated in Figs. 3 and 6.

The skip lever 21 is adapted and mounted, according to conventional practice, for two movements. The skip bar 21 is longitudinally shiftable in the conventional punching machine by one or more of the machine keys (not shown). In its retracted position (Fig. 1), the skip lever 21 has its outer end 22 resting on the machine frame edge 23 and is not engaged by the pins 41.

in the travel of the card carriage 11 over the machine frame 10. In the projected position (not illustrated) of the skip bar 21, its thickened portion 24 (Fig. 1) overlies the skip bar 31 and is in position to be engaged by the pins 41 set in the skip bar 31.

With the skip lever 21 in projected position and overlying an empty socket 33, the lever end 22 rests on the frame edge 23 and the escapement pawl 19 is free for normal single column escapement action with the rack 14. When the carriage 11 has advanced to such position that a pin 41 having a tapered head 42' (Fig. 4) engages the portion 24 of the lever 21, the head 42' exerts a camming action on the lever 21 and raises the lever 21 to elevate the escapement pawl 19 into a position in which it (19) disengages the escapement rack 14. This elevated position of the lever 21 and the pawl 19 is maintained as long as a pin 41 is below the projected lever 21. When a continuous series of sockets 33 are provided with pins 41 having flat top heads 42, as in Figs. 3 and 6, the projected lever 21 rests on the pin heads 42 and is maintained in elevated position as the pin heads 42 pass under the lever 21 during an advancing movement of the carriage 11. Thus a continuous series of pins 41 is adapted to cause an escapement of the card carriage 11, whereby the corresponding field of card columns is skipped; that is, the columns in the skipped field do not come to rest opposite the punching dies and therefore are not punched. Whenever the skip lever 21 is held in raised position by a pin 41, the escapement pawl 19 is prevented from engaging the escapement teeth 16 and the card carriage 11 is free to advance continuously. Advance of the carriage 11 is arrested when the skip lever 21 is lowered or the limit of movement of the carriage 11 is reached. The skip lever 21 is lowered by gravity action as soon as it is over an empty socket 33. It is now apparent that the setting of the pins 41 determines the escapement pattern, a pin 41 being set in each socket 33 corresponding to a card column which is not to be punched.

It is to be understood that the foregoing is illustrative since this invention includes all modifications and embodiments coming within the scope of the appended claims.

I claim:

1. A carriage escapement device comprising: means provided with escapement teeth, gear teeth, a row of sockets, and a passage extending along said row of sockets, said passage intersecting and opening into each of said sockets; a series of interchangeable, notched pins for selective setting in said sockets; and a needle adapted for insertion into said passage for such positioning therein that said needle extends into the notch of each of the pins in said sockets and thereby locks said pins to said means.

2. A carriage escapement device comprising: a skip bar, an escapement rack, a row of sockets in said skip bar, a series of interchangeable pins, each of said pins having a notched shank for selective positioning in said sockets, and a pin-locking needle, said bar being adapted to have said needle inserted therein and shifted axially to pass into the notches in the shanks of pins set in said sockets to lock the engaged pins to said skip bar.

3. A carriage escapement device comprising: a skip bar having a row of cylindrical sockets there-

in, the axes of said sockets extending in a plane parallel to the plane of a face of said bar, a plurality of pins, each pin having a head of larger diameter than a bar socket and a cylindrical shank adapted to be received in a bar socket, said shank having intermediate the ends thereof a peripheral groove, said bar face having a channel therein of a depth greater than the spacing of said sockets relative to said bar face and less than the spacing of the axes of said sockets relative to said bar face, a locking needle slidably and removably received within said channel, and an escapement rack secured to said bar to close the open side of said channel, said sockets, shanks, grooves, channel and needle being so related that the pin shanks are adapted to be selectively positioned in said sockets with the heads seated on the mouths of said sockets and that the needle is adapted to be inserted endwise into said channel and in its inserted position to extend through the shank grooves of all pins inserted in said sockets and thereby lock said pins in said sockets.

4. A carriage escapement device comprising: a skip bar having a row of cylindrical sockets therein, the axes of said sockets being perpendicular to one face of said bar and extending in a plane parallel to the plane of a second face of said bar, a plurality of pins, each pin having a head of larger diameter than a bar socket and a cylindrical shank adapted to be inserted into any one of said sockets, said shank having a peripheral groove spaced from said head; said second bar face having a longitudinally extending channel therein of a depth greater than the spacing of said sockets relative to said second bar face and less than the spacing of the axes of said sockets relative to said second bar face, said channel opening into each of said sockets and being spaced from said one bar face a distance corresponding to the spacing of said pin head and shank groove, an escapement rack secured to said bar to close the open side of said channel, and a locking needle adapted to be removably received within said channel and to slide endwise therein to a position in which said needle extends through the shank grooves of all pins inserted in said sockets and thereby locks said pins to said bar.

5. For use with an escapement rack of a carriage escapement device, the combination comprising: a skip bar having a row of cylindrical sockets therein, the axes of said sockets being perpendicular to one face of said bar and extending in a plane parallel to the plane of a second face of said bar, a plurality of pins, each pin having a head of larger diameter than a bar socket and a cylindrical shank adapted to be inserted into any one of said sockets, said shank having a peripheral groove spaced from said head; said second bar face having a longitudinally extending channel therein of a depth greater than the spacing of said sockets relative to said second bar face, said channel opening into each of said sockets and being spaced from said one bar face a distance corresponding to the spacing of said pin head and shank groove, and a locking needle adapted to be removably received within said channel and to slide endwise therein to a position in which said needle extends through the shank grooves of all pins inserted into said sockets and thereby locks said pins to said skip bar.

BENJAMIN GRADY.
